(57) **CLAIM**

The ornamental design for a container for storing liquid seasonings as shown and described.

DESCRIPTION

1. Container for storing liquid seasonings

1.1 : Front

1.2 : Top

1.3 : Bottom

1.4 : Right

1.5 : Left

1.6 : A-A Cross Section View

1.7 : B-B Cross Section View

1.8 : Perspective

1.9 : Perspective

This article is a container for storing liquid seasonings such as soy sauce. The liquid seasoning can be discharged by cutting along the cut line on the tip side.

1 Claim, 9 Drawing Sheets
